UNITED STATES PATENT OFFICE

2,272,103

ELEVATOR CANVAS

Thomas Williams, Emigrant, Mont.

Application November 30, 1940, Serial No. 368,051

1 Claim. (Cl. 198—199)

The present invention relates to an improved elevator canvas or apron particularly for binders, combines, reapers, threshing machines, etc. However, it will be understood that an elevator canvas or apron constructed in accordance with the present invention may be used for any purpose for which it may be found adapted and desirable.

An important object of the invention is to provide, in a manner as hereinafter set forth, an elevator canvas of the character described which will be free of the usual buckles, straps, rivets or staples and wherein the ends of the belt are held together by lacing.

Another very important object of the invention is to provide an elevator canvas of the aforementioned character comprising slats of a novel construction and arrangement.

Other objects of the invention are to provide an elevator canvas of the character set forth which will be comparatively simple in construction, strong, durable, highly efficient and reliable in use, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of an elevator canvas constructed in accordance with the present invention, portions thereof being broken away.

Figure 2 is a view in side elevation of an intermediate portion of the canvas.

Figure 3 is a bottom plan view looking at the connected end portions of the belt from the line 3—3 of Figure 2.

Figure 4 is a cross sectional view, taken substantially on the line 4—4 of Figure 2.

Figure 5 is a fragmentary view in vertical longitudinal section, taken substantially on the line 5—5 of Figure 4.

Figure 6 is a detail view in cross section, taken substantially on the line 6—6 of Figure 1.

Referring now to the drawings in detail, it will be seen that the embodiment of the invention which has been illustrated comprises a belt 1 of canvas or other suitable flexible material. The end portions of the belt 1 are folded at 2 and stitched for providing a double thickness of material in which eyelets 3 are mounted. The eyelets 3 accommodate a lace 4 of suitable material through the medium of which the ends

5 of the belt 1 are adjustably and detachably connected. One end of the belt 1 terminates in a flap 5 which is adapted to extend over the laced connection. Sewed on the inner longitudinal marginal portions of the belt 1 are strengthening or reinforcing strips 6 of suitable flexible material. The stitching which secures the strips 6 in place is indicated by the character 8 and extends longitudinally of the belt.

At longitudinally spaced points the belt 1 is folded transversely and stitched in a manner to form upstanding loops or pockets 7. The end portions of the transversely extending pockets 7 are flattened and secured to the canvas 1 by the 10 same stitches 8 which attach the strips 6. Then, one end portion of the loops forming the pockets 7 is cut transversely, as at 9, to form openings 15 for said pockets. This is shown to advantage in Figure 6 of the drawings. The other ends of the pockets 7 remain closed.

The pockets 7 are for the reception of removable rods 10 of suitable metal. Of course, the rods 10 are inserted in the pockets 7 at the open ends 9 of said pockets. The rods 10 are of sufficient length to project a slight distance beyond the open ends 9 of the pockets. Formed in the rods 10, adjacent the open ends of the pockets, are circumferential grooves or channels 11. Passing through the stitched lower portions 12 of the pockets 7, adjacent the open ends of said pockets, are ties 13. As also shown to advantage in Figure 6 of the drawings, the ties 13 are adapted to be drawn around the pockets 7 for gathering and contracting said pockets in the grooves 11 for securing the rods 10 in said pockets.

It will thus be seen that an elevator canvas has been provided which is free of buckles, straps, rivets, etc. Through the medium of the eyelets 3 and the lace 4 the ends of the canvas may be 20 expeditiously and securely connected. It will also be observed that the rods 10 constituting the slats are mounted and held on the canvas without the use of metallic securing elements. Should one of the rods 10 be bent it may be expeditiously removed for repair or replacement. To accomplish this it is only necessary to untie the ties 13. The stitching 8 extending through the end portions of the pockets as before described, will tend to prevent the stitching of the pockets extending transversely of the belt from tearing loose from stress acting longitudinally of the belt. The strips 6 also assist in preventing the pockets from tearing out by being secured to the end portions of the pockets by the stitching 8.

55 It is believed that the many advantages of an

elevator canvas constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

An elevator canvas comprising a flexible belt, said belt being folded transversely on itself at longitudinally spaced points and stitched for pro-

viding integral, tubular pockets, said pockets being open at one end and closed at their other ends, rods removably mounted in the pockets, said rods having circumferential grooves therein, and flexible ties positioned directly in the grooves at the bottom of the pockets and extending outwardly of the pockets transversely across the top thereof for gathering and engaging the material of said pockets in the grooves for removably securing the rods in said pockets.

THOMAS WILLIAMS.
